UNITED STATES PATENT OFFICE

WILLEM DE GROOT AND JOHANNES GIJSBERTUS WILHELM MULDER, OF EINDHOVEN, NETHERLANDS, ASSIGNEES TO N. V. PHILIPS' GLOEILAMPENFABRICKEN, OF EINDHOVEN, NETHERLANDS, A LIMITED LIABILITY COMPANY, OF THE NETHERLANDS

ELECTRIC ARC DISCHARGE TUBE

Application filed October 18, 1928, Serial No. 313,355, and in the Netherlands November 30, 1927.

The invention relates to arc discharge tubes comprising an incandescent cathode, preferably a Wehnelt cathode. In a prior specification Serial No. 162,896, filed January 5 22nd, 1927, in the name of Bruijnes, Oosterhuis & Mulder, a continuation of which, Serial No. 555,121 was filed on August 4th, 1931, is described an arc discharge tube filled with a gaseous atmosphere consisting of a mixture 10 of a rare gas and mercury vapour. Use should preferably be made of a mixture of argon and mercury vapour. Now the applicants have found that the gaseous filling contained in an arc discharge tube which 15 comprises an incandescent cathode, may contain, in addition to mercury vapour, another gas that is not a rare gas. Use should preferably be made of a filling of mercury vapour and hydrogen or of mercury vapour and nitrogen 20 but also other gases such, for example as carbon monoxide or carbon dioxide together with mercury vapour may give good results. In arc discharge tubes according to the invention may also be used mixtures of different 25 gases together with mercury vapour. Thus, for example, use may be made of fillings containing a rare gas, for example a small quantity of argon, in addition to mercury vapour and another gas that is not a rare gas.

30 The pressure of the gaseous filling should preferably be lower than some centimetres of mercury and the distance between the electrodes may be about 1 cm. The value of the arc voltage substantially depends on these two 35 values and principally on their product.

The invention will be more clearly understood by referring to the accompanying drawing which represents diagrammatically a discharge tube according to the invention which 40 acts as a rectifier. The discharge tube shown in the drawing comprises a bulb 1 of glass or similar material having hermetically sealed to it a glass tube 2 provided at its end with a pinch in which the supply wires 3 and 4 45 of a Wehnelt cathode 5 and the supply wires 6 and 7 of anodes 8 or 9 are hermetically sealed. The incandescent cathode is constituted by a preferably helically wound wire which is superficially coated with a material adapted to emit a large quantity of electrons 50 at a relatively low temperature, for example with barium, barium oxide or the oxide of another alkaline earth metal. This cathode may be manufactured by applying barium metal on a core wire, which metal may be 55 subsequently oxidized. Alternately, a core wire may be coated with a paste containing a barium compound which when heated yields the oxide. The cathode preferably consists of a wire of highly refractory metal, for example tungsten, on which a wire of a metal of lower melting point, for example nickel, is helically wound, the body thus produced being subsequently coated with an alkaline 60 earth or an alkaline earth oxide. The anodes 65 8 and 9 are constituted by plates of nickel, carbon of similar material. In the discharge tube has been volatilized a small quantity of magnesium or an alkaline earth metal which has deposited on the inner wall of the discharge tube. The gaseous filling may consist 70 of mercury vapour and hydrogen. The pressure of the gaseous atmosphere and the distance between the cathode 5 and the anode 7 are so chosen that the tension between the 75 electrodes is as low as possible. In some cases this tension may be smaller than the ionization voltage of the gas. Into the discharge tube has been introduced a small quantity of mercury so that the vapour pressure there- 80 of is determined by the temperature of the tube, said temperature being relatively low (under 100° C.). In a particular mode of realization in which the temperature of the Wehnelt cathode is 1000° C. and the pressure 85 of the hydrogen is 0.5 mm. while the distance between the electrodes is about 5 mm. the arc voltage may be about 10 to 15 volts.

With lower pressures of the gas or in discharge tubes adapted to rectify high-tension 90

alternating currents the distance between the electrodes may be of the order of some centimetres.

The discharge tube according to the invention is exceedingly well suited for charging batteries and operates with a higher efficiency than discharge tubes used for similar purposes which are not in possession of the features set forth in the present specification or in the said prior specification.

What we claim is:

1. An arc discharge tube, comprising a Wehnelt cathode, and an anode, the said tube containing liquid mercury, a rare gas, and a gas other than a rare gas.
2. An arc discharge rectifier tube, comprising a Wehnelt cathode, and an anode, and containing liquid mercury, a rare gas, and a gas other than a rare gas, wherein the distance between the electrodes is of the order of 1 cm., while the pressure of the gas is of the order of 1 mm. of mercury.

In testimony whereof we have signed our names to this specification.

25
